UNITED STATES PATENT OFFICE.

OTTO R. REINICKE AND CHARLES R. LEEMAN, JR., OF DETROIT, MICHIGAN.

COMBINED DOORCHECK AND DOOR BUMPER.

Application filed July 23, 1926. Serial No. 124,330.

This invention relates to a combined door check and door bumper, and has to do particularly with an extremely simple and efficacious device adapted to be moved to one 5 position to operate as a door check and to another position to operate as a door bumper.

Many attempts have hitherto been made to design a device adapted to have the double use of a door check and a door bumper, but 10 such devices of the prior art have either been inefficient in accomplishing their purpose or have been relatively complicated and expensive to manufacture.

The object of the present invention is to 15 provide a combined check and door bumper of extremely simple construction and one which at the same time will be efficient and positively operative to operate either as a door check or a door bumper, as desired.

20 In the drawings:

Fig. 1 is a perspective view illustrating the manner of attaching our novel device to the corner of a door.

Fig. 2 is a view similar to Fig. 1, but showing the operating member raised to a position where it operates as a door bumper.

Fig. 3 is a plan view of the structure positioned as shown in Fig. 2.

Fig. 4 is a section taken on the line 4—4 30 of Fig. 3.

Our device consists essentially of only two elements, a housing member which may be generally designated 1, and a movable operating member 2. This housing 1 is of extremely 35 simple construction, and is preferably formed with a single piece of material. In the present construction it is shown as being stamped out to form a housing rectangular in cross section and provided with two wings 3 and 40 4, whereby the housing can be secured to the lower corner of the door.

The portion of the housing adjacent the door is preferably open. The end portions, or top and bottom walls of the housing, are 45 provided with suitable centrally positioned apertures 5 and 6, said apertures being in longitudinal alignment. The operating member 2 consists merely of an L-shaped rod, one leg of said rod being designated 7 and 50 being adapted to extend downwardly through the apertures 5 and 6, and the other leg of the member 2 being designated 8, and being bent at right angles to the leg 7.

The rod 7 is provided with a suitable

washer 9 rigidly secured thereto, and adapted 55 to position the lower end of a suitable coil spring 10 which may be inserted through the open side of the housing 1 at the time of assembly. The top end of the housing 1 is provided with a small keyway or slot 11, and 60 the upper end of the rod 7 is provided with a small key or extension 12 adapted to co-operate with said keyway 11. The ends of the legs 7 and 8 are provided with suitable bumper members 13 and 14, the bumper 14 65 on the leg 8 being preferably of a greater diameter than the depth of the housing 1, whereby in case the door is pushed against the friction of the bumper 13, when said device is operated as a check, such bumper will 70 prevent marring of the door.

When it is desired that the device operate as a check, it will be only necessary to position the leg 8 parallel to the plane of the door whereby the key 12 will co-operate with the 75 keyway 11 when the force of the spring 10 will force the key 12 through such keyway 11 and allow the bumper 13 to be forced against the floor under the tension of the spring 10. This will effectively hold the door in any desired position. If it is desired that the device operate as a bumper, it is only necessary 80 that the operating member 2 be moved vertically until the key 12 is passed through the keyway 11 when the leg 8 may be moved at 85 right angles to the plane of the door in which position the bumper 14 will act as a positive bumper for the door. It will be understood that the key 12 is only of such length that it may easily pass or be vertically moved 90 within the coil spring 10.

Applicants are familiar with a number of devices of the prior art, but so far as applicants are aware, they are the first persons to provide an extremely simple, compact and inexpensive combined door check and bumper as shown in the drawings, and which device is movable vertically of the housing to act as a resilient check and which device is also movable vertically of the housing to release 95 the check and act as a positive door bumper.

It will be understood that the leg 8 may be turned at right angles to the door when the operating member is in its downward position to act as a door check when such leg 8 100 would act as a bumper in case the door was moved to overcome the friction between the bumper 13 and the floor. However, in its

preferred form, the bumper 14 is positioned adjacent the door to protect the door in case the friction of the bumper 13 were overcome.

What we claim is:

- 5 1. A combined door check and door bumper, comprising a housing, an operating member movable longitudinally of the housing, resilient means within the housing normally tending to force the operating means downwardly, a key on said operating means and a key-way on said housing for registering therewith, said operating member being operative in one position to operate as a door check, and adapted to be moved vertically, 10 and moved to another position to operate as a door bumper, and a third position in which it is totally inoperative.
2. A combined door check and door bumper, comprising a housing, an operating member movable longitudinally of said housing, means for attaching said housing to a door, cooperating means on said housing and said operating means for permitting the said operative means to be lowered to act as a check, or to be raised and latched to act as a bumper or to be placed in inoperative position.
3. A combined door check and door bumper, comprising a housing adapted to be attached to a door, the portion of the housing adjacent the door being open, apertures in the top and bottom walls of the housing for receiving a longitudinal movable operating member provided with a laterally extending top part, a coil spring insertable in the open top part, a keyway on the top part of the housing, and means forming a part of said housing provided with a keyway, and a key on said operative member adapted to register with said keyway when the top part is positioned in a plane parallel to the door, and adapted to be out of register when said top part is positioned at right angles to the door and also out of register when said top part is in a plane parallel to the door and when the operative member has been moved through an arc of 180°.
4. A combined door stop and door bumper, comprising a housing, a plunger movable within and longitudinally of said housing, one of the side walls of said housing being open for the reception of a coil spring, the upper end of said plunger being bent at substantially right angles to the portion within the housing, and means for holding the

plunger in raised position whereby it may be used as a bumper, said means also holding the plunger while in raised position in another and totally inoperative position, and means for permitting lowering of the plunger whereby it may be used as a check.

5. A combined door stop and door bumper, comprising a housing, a plunger movable within and longitudinally of said housing, one of the side walls of said housing being open for the reception of a coil spring, the upper end of said plunger being bent at substantially right angles to the portion within the housing, and means for holding the plunger in raised position whereby it may be used as a bumper, and means for permitting lowering of the plunger whereby it may be used as a check, the upper bent end of the plunger being movable in an arc of 180° when said plunger is in checking position.

6. A combined door stop and door bumpers, comprising a housing secured to a door and having upper and lower wall portions provided with openings, a plunger extending through the openings the lower end of which is adapted to engage the floor for serving as a door stop, spring means in the housing normally urging the plunger downwardly into door stopping position, the upper end of the plunger having a laterally extending arm, the upper end portion of the housing having a keyway, a key on the plunger, said key and keyway being positioned so as to align with each other when the laterally extending arm is in the plane parallel to the door with the arm extending in one direction from the housing, said plunger being rotatable in the housing whereby the arm can be positioned to extend outwardly at substantially right angles to the door with the keyway and the key disaligned, and with the end of the arm acting as a door bumper and with the key resting on top of the housing, thus holding the lower end of the plunger raised from the floor and whereby the arm can be positioned in a plane parallel to the door but extending in an opposite direction from the housing so that both the lower end of the plunger and the end of the arm are in inoperative positions.

In testimony whereof we have affixed our signatures.

OTTO R. REINICKE.
CHARLES R. LEEMAN, JR.
